UNITED STATES PATENT OFFICE.

SAMUEL M. ESLER, OF MCHENRY, ILLINOIS.

ELECTRICAL APPARATUS.

1,069,401.

Specification of Letters Patent.

Patented Aug. 5, 1913.

Application filed June 9, 1910. Serial No. 565,981.

To all whom it may concern:

Be it known that I, SAMUEL M. ESLER, a citizen of the United States, residing at McHenry, in the county of McHenry and State of Illinois, have invented new and useful Improvements in Electrical Apparatus, of which the following is a specification.

This invention relates to improvements in electrical apparatus.

10 More particularly, the invention is shown as it may be applied to a system for metering electric current, in which a person at a distance, as for example, at a center of distribution or a central station, desires at different times to shift the arrangements at the consumers' stations so as to operate the meter at different rates, or to register different percentages of the power passing. The apparatus is herein shown as it may be 20 applied to the particular variety of multiple meters in which there is a single recording apparatus and various means for operating that apparatus; and the invention relates to a device for shifting from one such means to another, so that, at the will of a person at a distance, either one of said operating means shall be put in operation. Hitherto, so far as I am aware, this has not been accomplished without the use of an extra wire 25 30 forming a part of an independent circuit by which the switch or other changing mechanism is operated. Although its application to only this particular apparatus is shown, it will be obvious that the invention 35 is not limited in its application to the specific apparatus herein shown and described, but may be applied in other connections and to different apparatus or for different purposes.

40 The objects of the invention are accomplished by providing a ratchet arrangement which is actuated by a magnet; and the magnet is actuated, without the use of any auxiliary or extra wire in addition to those 45 normally constituting the main circuit, by a momentary change in the potential of the main circuit.

The invention comprises means by which the desired effect may be attained by a complete interruption and restoration of the circuit, or in which it may be attained by a momentary reduction of potential not amounting to a complete interruption, yet will not result in case a complete interruption occurs. This is because it is desirable in some types of circuits that there should

be no complete interruption under normal conditions; and also because it is desirable in any circuit that an accidental interruption of the circuit, such as happens from time to time for brief periods, should not cause an unintended operation of the apparatus.

The invention comprises other features of novelty incidental to the apparatus and meter hereinafter described or shown in the accompanying drawings.

In the drawings, Figure 1 is an elevation of one type of apparatus embodying the invention, in one normal working position; Fig. 2 is an elevation of the same in a different normal working position; Fig. 3 is an elevation of the same in still a different normal working position; and Fig. 4 is a diagrammatical representation of a circuit embodying the invention.

Referring to the drawings, and more particularly to Fig. 4, an electrical generator is represented having poles 10 and 20 from which line wires, 11 and 21, and branch wires 12 and 22, lead to a meter 9; whence wires 13 and 23 lead to the load 8. In the meter the low resistance-coil, through which the current passes, is marked 6, and the high resistance-coil, which is connected across the poles is marked 7. A shunt across the meter is provided by means of wire 24, resistance 25, switch 26 and wire 27. The resistance 25 is represented as variable, but for many purposes a fixed resistance would serve all 90 needs. According to the total resistance of the shunt, including this resistance-coil 25, the amount of current which flows through the meter coil 6 varies; and consequently when the shunt is connected the meter registers only a fraction of the power actually passing from the main line to the load, instead of registering it all as it does when the shunt is not connected. Means is provided to connect and disconnect this shunt, 100 consisting of a switch 26 which is actuated by a gear 30, meshing with and driven by a gear 31, which in turn is actuated by a ratchet 32 driven step by step by a pawl 33. The pawl is actuated by an armature 34 of a magnet 35, energized by a coil 36 which is connected to the main line wires through wires 18 and 28. Upon a reduction of potential in the main line the pull of the magnet 35 on its armature 34 is reduced. When low enough, the armature falls from the position seen in Fig. 1 to 110

that seen in Fig. 2, the pawl moving down as indicated. When the normal potential is restored, the armature is drawn back to the position seen in Fig. 1; and the pawl, having fallen far enough to engage the next tooth of the ratchet 32, causes the ratchet and gear 31 to rotate, thus turning the small gear 30 and the switch 26. As illustrated, the ratio of gearing is such that a quarter turn of the switch 26 corresponds to one tooth of the ratchet. Consequently, whichever position the switch be in, a movement of the ratchet one step will turn it to its other position, the two positions being illustrated in Figs. 1 and 2. A pin 37 is provided, which limits the downward movement of the armature and pawl.

In some cases an additional feature of the invention may be added. This is shown in all the figures of the drawing, and consists of an armature 40 at the other end of the magnet, held on a lever 40' pivoted at 41 and provided with a spring 42 which tends normally to raise the armature. A keeper 43 hangs from the lever and has a lug 44 under the lever which holds pawl 33, so arranged that when the armature 40 is up, as shown in Fig. 3, against its stop pin 45, lug 44 is high enough to hold pawl 33 too high to engage in the next lower tooth of the ratchet, as seen in Fig. 3. The parts should be adjusted with respect to strength of magnet, spring, etc., so that a reduction in voltage in the line of about thirty to fifty per cent. will release the lower armature 34, but not the upper armature 40. In case the circuit is broken entirely, the armature 40 is released so that the spring 42 acts to raise lever 40'. The lug 44, rising with it, holds the pawl too high to engage in the next tooth of the ratchet, as above described.

Fig. 1 shows the apparatus in one normal condition of use, in which the switch 26 is closed and, the shunt being thus connected, only a portion of the current passes through the current coil 6 of the meter, and therefore only a portion of the energy used is registered by the meter. What proportion that is, is determined by the resistance of the shunt with relation to the current coil 6, and that proportion may be adjusted or altered at will by adjustment of the variable resistance 25, or it may be fixed once for all by providing a shunt whose total resistance is not variable.

It is contemplated that a distribution system of electricity to various consumers may be provided with a device of the sort described at each consumer's place. A similar apparatus, to serve as a pilot, may be installed at the central station or point of control. During certain hours the switch 26 will be open, allowing the meter to register the full amount of energy which is being consumed. If, however, it be desired, at cer-

tain hours of the day, to encourage the use of electricity by reducing the charge to consumers, this may be effected by throwing all of the meters into the position in which they register but a portion of the energy consumed; and this change of the meters would be accomplished by actuating the various switches 26. This in turn is effected by a momentary reduction of the main line voltage, followed by a restoration to normal. Assuming that the upper armature 40 and its connected parts be omitted, any reduction of the voltage sufficient to release armature 34, whether amounting to a complete interruption of current or not, would be sufficient to actuate the apparatus. The pilot at the control station would at any time show the operator the condition in which meters in all parts of the system were standing; so that if any extraordinary or unintended interruption or reduction of voltage occurred, setting the meters in a position not desired, he could set them right by repeating the interruption. If the armature 40 and its connected parts be added to the apparatus, a reduction of voltage to a predetermined amount would let armature 34 down to the position shown in Fig. 2, without releasing armature 40. The depending keeper 43 is long enough so that its lug 44 will not be reached under these conditions, in which the armature 40 is held by the magnet. Upon the restoration of voltage in the main line, armature 34 will be raised and the switch 26 actuated.

Fig. 2 represents the apparatus during such a momentary reduction of voltage in which the parts are in the position preceding that which they occupy in Fig. 1. If a complete interruption of the circuit occurs, or so great a reduction of voltage as to release the armature 40, both armatures begin simultaneously to move away from the magnet, and it follows that before the armature 34 has fallen far enough for its pawl to engage the next tooth of the ratchet, the spring 45 has lifted the keeper 43 and lug 44 far enough to prevent such engagement. The keeper holds it so: and when normal potential is restored in the line, and the magnet draws armature 34, the pawl does not actuate the switch.

While the drawings illustrate an improved method of altering the recording action of the meters, the switch might actuate some other, whether mechanical or electrical, method of changing the reading of the meter. It will also be obvious that the invention herein disclosed is applicable to other uses, and may operate devices other than the specific device and application of the invention herein disclosed, it being competent by this means to actuate any contrivance at a distance from the controlling operator without the aid of an auxiliary

wire, but merely by reduction and restoration of the voltage in the main wires.

I claim as my invention and desire to secure by Letters Patent:—

- 5 1. The combination of an electro-magnet; an armature drawn by it; another armature, mounted and adapted to be magnetically drawn by the same current that draws the first armature; said magnet and armatures 10 being arranged for forces, acting on the armatures and weaker than the said magnetic forces acting thereon, to withdraw the armatures when the current strength is sufficiently reduced; a greater reduction of 15 current strength being required to release the second armature than is required to release the first; and a keeper for the first armature, attached to the second armature and adapted to limit the withdrawal of the 20 first armature whenever the second armature is simultaneously withdrawn.
2. The combination of an electro-magnet; an armature, these being mounted and arranged so that upon reduction of the magnet strength to an abnormal degree, a force 25 weaker than the normal magnet strength may move the armature away, the armature moving toward the magnet again upon restoration of magnet strength; and means to prevent movement of said armature to its full distance from the magnet, said preventive means being normally held in inopera-
3. A mechanism, comprising in combination an electric conductor and a moving part controlled by current normally flowing through the conductor; movement of said part being controlled by change of the current between a normal value and an abnormally reduced value; and means holding said part, when the current is interrupted, without effectual recession from its position which corresponds to normal current flow.
4. A device adapted to be controlled by current from supply conductors and having a movable member actuated by abnormal reduction in the flowing current, said member being held against effective actuation, and in approximately the position corresponding to normal flow, when the flow of current ceases suddenly.

Signed by me at McHenry, Illinois, this first day of June, 1910.

SAMUEL M. ESLER.
